Specification for Design.

Patented Mar. 15, 1921.

Application filed September 20, 1920. Serial No. 411,679. Term of patent 14 years.

To all whom it may concern:

Be it known that I, ORLANDO L. WEAVER, a citizen of the United States, residing at Akron, in the county of Summit and State of Ohio, have invented a certain new, original, and ornamental Design for Tire-Casings, of which the following is a specification, reference being had to the accompanying drawings, forming a part thereof.

In the drawings,

Figure 1 is a perspective view of a frag-

ment of a tire casing showing my new design, and

Fig. 2 is a plan view thereof.

I claim:

The ornamental design for a tire casing, as shown.

In testimony whereof I affix my signature.

ORLANDO L. WEAVER.
